UNITED STATES PATENT OFFICE.

JAMES G. DELANEY, OF NEW YORK, N. Y.

DUMPING APPARATUS.

SPECIFICATION forming part of Letters Patent No. 595,528, dated December 14, 1897.

Application filed April 9, 1897. Serial No. 631,411. (No model.)

To all whom it may concern:

Be it known that I, JAMES G. DELANEY, of New York city, in the county and State of New York, have invented a new and Improved 5 Dumping Apparatus, of which the following is a full, clear, and exact description.

The purpose of this invention is to provide an improved dumping apparatus by which a load-receptacle or bucket may be raised, lowered, or conveyed and, when desired, dumped.

The invention is susceptible of use in various connections, such as transfer or cable systems, but in the drawings it is shown applied to a derrick as one application of the 15 invention.

The invention will be fully described hereinafter and its scope defined in the claims.

Reference is to be had to the accompanying drawings, forming a part of this specification, 20 in which similar characters of reference indicate corresponding parts in all the figures.

Figure 1 is a side elevation of the invention in use. Fig. 2 is a vertical section taken through the fall-block. Fig. 3 is an end view 25 of the fall-block and skip or load-receptacle, and Fig. 4 is a detail section taken through the pulley of the fall-block.

According to the specific device given in the drawings as an illustration, the boom 5 of the derrick has a block 6 swiveled thereon and carrying a cable 7, which runs in the usual manner around the sheave or pulley 8 of the fall-block. Interposed between sections of and forming part of the cable 7 is a chain 9, the links of which are wider than the thickness of the remaining portion of the cable, so that portions of the links will project beyond the sides of the sheave 8 of the fall-block. This chain 9 may, if desired, be substituted by any device which increases the size of the cable at a certain point. It is not essential that the specific chain be used, as will more fully appear hereinafter.

The fall-block is shown as having two vertically-extending frame-plates 10, rigidly joined to each other at their upper and lower ends by transverse pins 14^a. Intermediate portions 11 of the frame-plates 10 are projected outwardly and fixedly carry a transverse pin or shaft 12. Respectively engaging the frame-plates 10 are the cheek-pieces 13 of the fall-block, which are joined to each

other at their outer edges by means of transverse pins 14. The sheave 8 of the fall-block is mounted loosely on the center of the shaft 12. Loosely mounted on the shaft 12, and one on each side of the sheave 8, are the two winding-drums 15, the inner ends of each of which respectively project through openings in the cheek-pieces 13 and respectively rigidly carry annular plates or disks 16, which lie adjacent to the respective sides of the sheave 8 and preferably have a diameter greater than that of the sheave, so that the peripheries of the plates or disks 16 will project beyond the periphery of the sheave. The main portions of the drums 15 project outwardly beyond the cheek-pieces 13 and are embraced by the outwardly-extended portions 11 of the frame-plates 10. Fixed to each drum 15 is a staple 17, to which the chains 18 are respectively connected. The chains 18 are also connected with the rear end of the load-receptacle, skip, or bucket 19. The load-receptacle or bucket 19 is provided at its center with a cross-bar 20, with which a hook 21 connects, the hook being carried by the pin 14^a, which passes transversely between the frame-plates 10 at the lower ends thereof.

The cable 7 passes around the sheave 8. 80 The load in the receptacle 19 so disposes the receptacle that the chains 18 or equivalent carrying devices are held taut in the positions shown by full lines in Figs. 1 and 3. As the cable 7 runs around the sheave 8 and when 85 the chain 9 engages the sheave the links of the chain 9, being wider than the cable 7 is thick, will project laterally to engagement with the notches 16^a in the inner faces of the disks or plates 16. This will cause the disks 90 or plates 16 to be revolved and the chains 18 will be wound on the drums. This will draw up one end of the bucket or load-receptacle 19 and the same will be dumped, as the dotted lines in Fig. 1 show.

It will be understood that the particular devices shown are given for the purpose of illustrating one specific embodiment of my invention and are not the measure of the general invention hereinafter defined in the claims, 100 to which latter the language measuring the scope of the invention is properly relegated. Thus generically the drums are devices mounted to be turned, and the drums or ap-

purtenant part or parts thereof are directly engaged to dump the load by the chain-links or any other suitable trips in the path of the engaging appurtenant parts of the drums, the 5 rotative movement of said trips and the drums or their appurtenant trip-engaging parts serving directly to effect the turning movement.

It will be seen that this dumping of the receptacle takes place no matter in which direction the chain 9 moves relatively to the fall-block or similar device embodying my invention. It will also be seen that the chain 9 may be substituted by any device which will engage with the plates or disks 16. The 10 connection which causes the drums 15 to wind the chains 18 is not with the sheave 8, but is directly with the element which turns the drum. The sheave 8 performs no function 15 in the dumping operation. It is merely useful for carrying the cable, and any other device which can serve such function may be used in place of the sheave. The operation of the drums 15 is independent of the operation of the sheave, since, if desired, one cable 20 may be run around the sheave to support the fall-block and a second and separate means 25 provided to transmit movement to the drums.

Having thus described my invention, I claim as new and desire to secure by Letters 30 Patent—

1. The combination with a frame, of a winding-drum mounted therein, a sheave mounted adjacent to the winding-drum, the sheave being capable of carrying a cable and being 35 freely movable in each direction independently of the winding-drum, and the winding-drum being capable of connection directly with the cable, whereby it is operated by the cable, substantially as described.

2. The combination with a frame, of a winding-drum mounted on the frame, and a sheave 40 mounted on the frame adjacent to the winding-drum and capable of turning freely in each direction independently of the winding-

45 drum, the winding-drum having a member in connection therewith, such member being located adjacent to the sheave and being capable of locking with the element that engages the sheave, whereby motion is transmitted 50 directly from said element to the winding-drum irrespective of the operation of the sheave, substantially as described.

3. The combination with a frame, of a winding-drum mounted thereon, a plate or disk 55 fixed to the winding-drum, and a sheave mounted to turn freely in both directions independently of the winding-drum, the sheave being located adjacent to coat with the means by which the frame is supported, the plate or 60 disk being capable of engaging directly with an element having movement relative to the frame, whereby the winding-drum is operated directly from said relatively-moving element irrespective of the movement of the sheave, 65 substantially as described.

4. The combination with a frame, of a shaft mounted therein, a winding-drum mounted

70 to turn freely on the shaft, a sheave mounted on the shaft, and a plate or disk in rigid connection with the winding-drum and located adjacent to the sheave, the sheave and winding-drum being each operative independently of each other, substantially as described.

5. The combination with a frame, of a shaft 75 mounted therein, a winding apparatus carried by the shaft, and means also carried by the shaft for engaging an element by which the frame may be supported, the winding apparatus and said means being independently operative, and the winding apparatus being 80 capable of directly engaging a part having movement relative to the frame, whereby to operate the winding apparatus from said part irrespective of said means, substantially as 85 described.

6. The combination of two frame-plates 90 having rigid connection with each other, and each having an outwardly-extending intermediate portion, a cheek-piece adjacent to each frame-plate, a shaft extending transversely between the outwardly-extending portions of the frame-plates, a sheave mounted loosely on the shaft, two drums mounted loosely on the shafts and respectively on the sides of the sheave, the drums respectively 95 extending into the outwardly-extending portions of the frame-plates, and a plate or disk attached to the inner portion of each drum and respectively lying adjacent to the sides of the sheave and inside of the cheek-pieces, 100 substantially as described.

7. The combination with a frame, of a shaft 105 mounted therein, two cheek-pieces carried by the frame and through which the shaft extends, a sheave mounted on the shaft between the cheek-pieces, two drums mounted on the shaft and respectively on the sides of the sheave, and a plate or disk carried by the inner end of each drum and respectively adjacent to the sides of the sheave, substantially 110 as described.

8. The combination with a frame, of a shaft 115 carried thereby, a sheave loose on the shaft, a winding-drum also loose on the shaft, and a member carried by the winding-drum and located adjacent to the sheave, the member having portions projected beyond the periphery of the sheave and provided with notches capable of being engaged by a chain passing over the sheave, substantially as described. 120

9. A dumping apparatus mounted to travel, and having a winding device adapted for connection with a load-receptacle, and a strand passing adjacent to the winding device and having means to engage the winding device 125 and turn the same directly by the relative movement of the strand and dumping apparatus, substantially as described.

10. A dumping apparatus having a device adapted to turn, and having means for affording connection with a load-receptacle, and an engaging device in the path of the device to be turned, to effect the turning, substantially as described.

11. A dumping apparatus, comprising a sheave, a winding device having appurtenant parts adjacent to the sheave, and a strand serving to directly engage the said appurtenant parts, to directly operate the winding device, substantially as described.

12. The combination of the carrier, tripping devices toward and from which the car-

rier travels, and a winding device mounted on the carrier and adapted to be tripped by the said tripping device when the carrier in its travel reaches the said tripping devices.
